BELT SANDER

Herbert E. Tautz, Milwaukee, Wis., assignor to
 The Delta Manufacturing Company, Milwaukee,
 Wis., a corporation of Wisconsin

Application October 16, 1937, Serial No. 169,408

13 Claims. (Cl. 51—135)

The invention relates to abrading machines and more particularly to belt sanders and the like.

Belt sanders as heretofore constructed have been open to various objections, such as inadequate dust removal, unsatisfactory and inconvenient adjustment of the abrasive belts, incomplete guarding, and interference of enclosures and other parts with belt changing and with operations on certain classes of work.

It is an object of the present invention to provide a belt sander having improved enclosure means including readily removable guards permitting easy changing of the abrasive belt, and avoiding interference with operations on certain types of work.

Another object of the invention is to provide a belt sander which is capable of efficient dust removal.

Still another object of the invention is to provide a belt sander having a movable dust deflector or interceptor which is adjustable to avoid interference with certain types of work.

A further object is to provide an improved pulley mounting which is capable of easy and accurate adjustment for tensioning the abrasive belt and for causing the belt to run true.

A still further object is to provide a belt sander which can readily be adjusted for operation in either a horizontal or a vertical position.

The invention further consists in the several features hereinafter described and claimed.

In the accompanying drawings,

Fig. 1 is a side elevation of a belt sander constructed in accordance with the invention, the sander being arranged for horizontal operation and being equipped with an adjustable work stop, and another position of the work stop being indicated in dotted lines;

Fig. 2 is a top plan view of the sander;

Fig. 3 is an elevation of the other side of the sander, the machine being arranged for vertical sanding and provided with a tilting table for the work;

Fig. 4 is a side elevation of the sander in horizontal position, with guards removed, and equipped with a work-guiding fence;

Fig. 5 is a detail elevation of a side guard for the sander;

Fig. 6 is an elevation of the idler pulley end of the sander, the belt and an end guard being removed, and parts being broken away and parts being shown in section;

Fig. 7 is a detail view of an inner dust deflector for the sander;

Fig. 8 is a sectional view taken generally along the line 8—8 of Fig. 1;

Fig. 9 is a sectional view taken generally along the line 9—9 of Fig. 8, the abrasive belt being re-moved;

Fig. 10 is a sectional view taken generally along the line 10—10 of Fig. 8;

Fig. 11 is a sectional view taken generally along the line 11—11 of Fig. 8;

Fig. 12 is a sectional view taken generally along the line 12—12 of Fig. 4, but with the side guard replaced;

Fig. 13 is a detail view of the end guard;

Fig. 14 is a perspective view of an adjustable dust interceptor or deflector;

Fig. 15 is a detail sectional view of an adjusting device for the idler pulley, and

Fig. 16 is a top plan view of the tilting table of Fig. 3.

In these drawings, 20 designates a hollow, internally ribbed base having openings 21 for fastening bolts, not shown. A hollow, internally ribbed housing or supporting member 22 is suitably secured to the top of the base, as by screws 20 23, and is provided with spaced ball bearings 24 and 25 on which a horizontal drive shaft 26 is mounted, the opposite ends of the shaft projecting through the housing. One end of the shaft 26 carries a drive pulley 27 and the other end carries a drum pulley 28, the latter being secured on the shaft by a nut 29 and preferably being in the form of two hollow, internally ribbed halves placed end to end on the shaft.

The side of the housing or supporting member 30 adjacent the drum pulley 28 is in the form of a hollow hub-like pivot projection 30 concentric with the shaft 26 and having an annular clamping shoulder 30', Fig. 8, the ball bearing 25 being carried in a reduced end portion of the projection. An elongated, hollow, arm-like frame member 31 has a transversely apertured end portion 32 which is pivotally carried on the housing projection 30 and is swingable thereon to different angular positions, more particularly 35 horizontal and vertical positions. The horizontal position of the frame member 31 is determined by an adjustable stop stud 33 upstanding from the base 20 and having a supporting engagement with the frame member. The frame 40 member engages the annular shoulder 30' on the housing projection 30 and is clamped in its adjusted position against this shoulder by headed clamping screws 34 threaded into a clamping ring 35, Figs. 8 and 9. The screws 34 extend 45 through the housing 22 parallel to, and on opposite sides of, the shaft 26, and the clamping ring 35 fits in and engages an annular rabbet 36 formed in the frame member at the side adjacent the drum pulley 28. The frame member 50 and housing when clamped together form, in effect, a rigid frame which supports the pulleys and guards one side of the abrasive belt drive. The reduced end portion of the housing projection 30 extends beyond the frame member 31 and 55 60

clamping ring 35, so that the bearing 25 can be brought close to the pulley 28.

The outer or free end of the swingable frame member 31 is of C-shaped cross-section and is provided at the inner sides of its upper and lower portions with parallel keyways 37, Figs. 6 and 10, extending longitudinally of the frame member. Keys 38 are slidably mounted in the respective keyways. A hollow, forked pulley-supporting arm or bracket 39 fits between the keys 38 and is pivotally carried on a pintle 40 the opposite ends of which are journaled in the keys, the axis of the pintle being substantially perpendicular to the plane of the top flight or run 15 of the belt. A shaft 41 extends substantially parallel to the pulley drum shaft 26 and is journaled at opposite ends on ball bearings 42 carried by the forked bracket, one of the bearings being adjacent the pintle 40. An idler drum pulley 43 is carried on the shaft 41 and is similar to, but smaller than, the drum pulley 28.

The two drum pulleys are connected by an endless abrasive belt or band 44. The straight upper or active flight of the belt bears on a table 45 the opposite ends of which are adjacent the drum pulleys. The table is suitably ribbed and flanged on its under side and is rigidly secured to the hollow frame member 31 by screws 46. If desired, the flat top surface of the table may be 20 diagonally grooved, as shown, or otherwise relieved, so as to facilitate machining and to provide an improved backing support for the belt. The drum pulley 28 is sufficiently large in diameter to provide adequate belt traction without 25 using a rubber or other special facing.

Means are provided for adjusting the idler drum pulley 43 so as to facilitate changing of the belt and also to effect proper tensioning of the belt and to cause the belt to run true on the 30 pulleys. The angular position of the bracket 39 is adjusted by a screw 47 threaded transversely through the outer wall of the frame member 31 and engaging the bracket at a distance from the pintle 40, the screw 47 being locked in adjusted 35 position by a hand nut 48. The bracket 39 has a rounded heel 49 which is engaged by a lever 50, Figs. 8, 10 and 15, mounted within the hollow frame 31 on a horizontal pin 51 carried on the frame and extending transversely of the frame member. The lever 50 has a forked end embracing a sleeve or tubular member 52 of square cross-section which is slidably mounted on a shaft 53. The shaft is journaled at its upper end in the frame member 31 and at its lower 40 end in a bearing cap 54 secured by screws 55 to the apertured lower portion of the frame member. The shaft 53 is confined against axial movement by a crank handle 56 secured to the lower end of the shaft and by a collar 57 pinned to the 45 shaft above the bearing cap. A coiled spring 58 surrounding the shaft below the tubular member urges the latter upwardly. A coiled spring 59 surrounding the shaft within the tubular member urges the latter downwardly and is 50 compressed by a nut 60 engaging a screw-threaded portion of the shaft and non-rotatably fitting within the tubular member. The two springs are seated on shouldered portions of the tubular member. The upper end of the tubular member 55 55 carries ledges or flanges 61 at opposite sides provided with concave lower faces or shoulders 62 engaged by the convex upper faces 63 of the forked lever 50. By screwing the nut 60 downwardly the tubular member 52 is also moved 60 downwardly, and the forked lever 50 is caused to 75

swing outwardly, thus sliding the pulley-supporting bracket 39 outwardly along the keyways 37 and increasing the tension on the belt.

The shaft 53 and the several parts mounted thereon form a sub-assembly which is readily 5 mounted in place by inserting it into the apertured frame member 31 and fastening the bearing member 54 by the screws 55.

The drum pulley 28 is partially enclosed by a hood or guard 64 which is somewhat wider than 10 the length of the pulley and is provided with in-turned flanges 65 and 66 at opposite sides. The flange 65 is secured to a marginal flange 67 of the frame member 31 by screws 68. A spout 69 is formed on the hood to constitute a dust outlet 15 conduit and is adapted for connection to a suitable receptacle or vacuum dust collector, not shown.

A dust interceptor 70, Figs. 7 and 9, extends 20 across the bottom portion of the hood near the spout enlargement and is rigidly secured thereto by screws 71. The interceptor has a curved vane or lip 72, the upper edge of which lies close to the abrasive belt.

The upper edge of the hood 64 lies slightly below 25 the plane of the upper flight of the abrasive belt and has lugs 73 at opposite sides to which a transversely extending dust deflector 74 is pivotally secured by screws 75, the deflector having 30 screw-threaded lugs 76 near its ends to receive the screws, and having inturned or downwardly projecting wings or flanges 77 at its ends to minimize lateral discharge of the dust impinging on the deflector. The pivotal axis of the deflector extends substantially parallel to the shaft 35 26. The deflector is frictionally held in adjusted position and forms an extension of the hood. For ordinary sanding or polishing the deflector is swung upwardly to project above the extended plane of the upper flight of the abrasive belt at 40 40 an acute angle to the belt flight, as seen in Figs. 1 and 9, so as to form a scoop for catching practically all of the dust, and when long pieces are to be abraded the deflector is swung downwardly toward the pulley 28 and to the level of the table, 45 as seen in Fig. 4, so as not to interfere with the work.

A panelled, trough-shaped, sheet metal bottom guard plate 78 has upstanding side flanges 79 and 80. The flange 79 is clamped to the frame 50 flange 67 by screws 81 threaded into clamping bars 82, the guard plate flange being slotted or notched to receive the screws. One end of the bottom guard plate is received in a positioning groove 83, Fig. 9, formed in the edge of the hood 55 64.

A sheet metal side guard plate 84 bears at its lower edge against the flange 80 of the bottom plate, and bears at its upper edge against the side edge of the table 45, to which it is removably 60 secured by a thumb screw 85, the thumb screw passing through an opening 85' in the guard plate and being screw-threaded into the table. One end of the guard plate 84 has an arcuate edge 86 which enters a positioning groove 87 65 formed in the edge of the hood flange 66, and the other end is bulged at 88 to clear the idler pulley bracket 39. The side guard plate is readily removed so as to facilitate changing of the abrasive belt. The grooved arcuate edge of the hood 64 is 70 formed to a radius slightly larger than the radius of the drum pulley 28.

The idler drum pulley 43 is housed in an end hood or guard 89 which telescopes over the end 75 of the machine and is detachably secured there-

to by a hand nut 90 on a stud 91 screw-threaded into the end of the frame member 31, the stud passing through an opening 92 in the guard and between flanges 93 formed on the guard and engageable with the end of the frame member. The guard also has positioning dowels 94, Fig. 11, which enter openings 95 formed in the end of the frame member. The side edge of the guard 89 has a positioning channel or rabbet 96 to receive the end of the side guard plate 84, and the bottom edge of the guard 89 has a positioning groove 97 to receive the end of the bottom plate 78. For sanding long pieces, the guard 89 may readily be removed. The guard is also removed when changing the abrasive belt.

The work is guided on the machine in various ways. In Figs. 1, 2 and 8, the machine is provided with an adjustably mounted back stop 88 for small flat work, the stop extending across the belt to prevent the work from being carried along the belt. The stop is detachably secured by a screw 99 to a longitudinally slotted bar 100. A stud 101 is threaded into the outer side of the frame member 31 parallel to the shaft 26 and extends through the slotted bar 100, the bar being clamped to the frame member by a handle nut 102 on the stud. Another position for the back stop is indicated by dotted lines in Fig. 1.

In Figs. 4 and 12, the machine is shown to be provided with a fence 103, which is used for certain types of work, such as edge sanding of long pieces. The fence is secured by screws 104 to the ends of a pair of longitudinally slotted bars 105. Upstanding studs 106 are removably screw-threaded into openings 107 in the top surface of the frame member 31 and pass through the slotted bars, the bars being clamped in place by handle nuts 108 on the studs. Washers 109 below the bars serve to space the bars and fence 40 above the abrasive belt. The fence is adjustable across the width of the table so as to distribute wear on the belt.

For certain classes of work it is desired to have the active flight of the belt extend vertically, and for this purpose the frame member 31 is swung about its pivotal mounting to a vertical position, as seen in Fig. 3. For use in this position, the machine is provided with a tilting table 110 having a groove 111 for guiding a miter gage, not shown. The table is secured by screws 112 to a hollow arm 113 which is provided with an arcuate trunnion rib 114 fitting in an arcuate trunnion groove 115 formed in the outer side face of the frame member 31, the pivotal axis of the table 55 being parallel to the shaft 26 and lying substantially in the plane of the working flight or run of the abrasive belt. The trunnion arm 113 has an arcuate slot 116 receiving the stud 101 and is clamped in angularly adjusted position by a handle nut 117 on the stud. A scale 118 is secured to the frame member and cooperates with an index pointer 119 on the arm. A swingable stop 120 on the frame member cooperates with adjustable stop abutments 121 on the arm for facility in obtaining accurate positioning of the table 65 in various much-used angular positions.

In setting up the machine for use, the guards 84 and 89 are removed from the machine to permit the abrasive belt 44 to be mounted on the 70 drum pulleys, the idler pulley being slackened by the crank handle 56 to facilitate mounting of the belt. The idler pulley is then readjusted by the screw 47 and crank handle 56 to tension the belt and to cause it to run true. The spring 59 in the 75 pulley-shifting device prevents excessive tension-

ing of the belt and also avoids damage to the belt if the belt should shrink. The side guard 84 is then replaced, and in many instances the end guard 89 is also replaced. The appropriate work-guiding device is mounted on the machine, 5 and in some cases the machine is placed in the vertical position shown in Fig. 3.

In operation, the driving drum pulley 28 is rotated in the proper direction, causing the working or active flight of the abrasive belt to move 10 toward the hood 64. The work is then applied to the belt, causing the work to be sanded, smoothed, polished, or otherwise finished, according to the nature of the belt. The dust from the operation passes along the belt and is intercepted by the 15 adjustable deflector 74 so as to pass into the hood 64 and be drawn off through the spout 69, the interceptor 10 minimizing the flow of dust beyond the spout enlargement of the hood. The idler pulley can readily be adjusted while the belt is 20 running and without removing guards or other parts.

The enclosure of the machine not only reduces 25 flying dust but also guards both the machine and the operator from injury.

The machine can be used not only for sanding or smoothing wood, but also for polishing or finishing metal and other materials.

What I claim as new and desire to secure by 30 Letters Patent is:

1. In an abrading machine, the combination of means for supporting and driving an abrasive belt which presents a work-abrading flight, said means including a pulley over which the belt passes and toward which said flight travels, a 35 dust-collecting guard hood for said pulley having a portion adjacent to the plane of said belt flight, and a scoop-forming deflector shiftably carried by said guard hood to project beyond the plane of said belt flight for directing dust from 40 said flight into said guard hood, said deflector being mounted on said hood adjacent to the plane of said belt flight and being adjustable laterally of the plane of said belt flight to avoid interference with long work. 45

2. In an abrading machine, the combination of means for supporting and driving an abrasive belt which presents a work-abrading flight, said means including a pulley over which the belt passes and toward which said flight travels, and 50 dust-collecting means including a shiftably mounted scoop-forming deflector adjacent to said pulley to project beyond the plane of said belt flight for intercepting dust passing along said flight, said deflector having a free edge portion which is normally at an acute angle with respect to the plane of said belt flight, and said deflector being adjustable laterally of the plane of said flight to avoid interference with long work. 55

3. In an abrading machine, the combination of means for supporting and driving an abrasive belt which presents a work-abrading flight, said means including a pulley over which the belt passes and toward which said flight travels, a dust collector adjacent to said pulley, and a dust deflector pivotally mounted on said collector adjacent to the plane of said belt flight and forming a scoop-like extension of said collector for directing dust from said flight into the collector, said deflector being swingable outwardly to scoop-forming position and being swingable inwardly toward said pulley to avoid interference with long work, said deflector when swung outwardly projecting beyond the plane of said belt flight. 60

4. In an abrading machine, the combination of 70

spaced pulleys for supporting an abrasive belt which presents a work-abrading flight, the axes of said pulleys being substantially parallel, a bracket rotatably carrying one of said pulleys, a support having guideways parallel to said belt flight, members slideable along said guideways, said bracket fitting between said members to slide therewith and pivotally mounted thereon to swing about an axis substantially perpendicular to the plane of said flight, and means for sliding said bracket along said guideways and for angularly displacing said bracket on its pivotal mounting.

5. In an abrading machine, the combination of a frame, spaced pulleys carried on and projecting laterally from said frame for supporting and driving an abrasive belt, a table secured to said frame for backing the work-abrading flight of said belt, a dust-collecting hood secured to said frame for enclosing one of said pulleys and having a dust outlet conduit, a bottom guard secured to said frame, and a detachably mounted side guard extending from said table to said bottom guard and from said pulley-enclosing hood to a point adjacent to the other pulley, said pulleys being carried on said frame independently of said side guards.

6. In an abrading machine, the combination of a frame, spaced pulleys carried on and projecting laterally from said frame for supporting and driving an abrasive belt, a table secured to said frame for backing the work-abrading flight of said belt, a dust-collecting hood secured to said frame for enclosing one of said pulleys and having a dust outlet conduit, a bottom guard secured to said frame, a detachably mounted side guard extending from said table to said bottom guard and from said pulley-enclosing hood to a point adjacent to the other pulley, and an end guard for the other pulley detachably secured to said frame and engaging the adjacent ends of said bottom guard plate and side guard plate, said pulleys being carried on said frame independently of said side guard.

7. In an abrading machine, the combination of a supporting member having a pivot portion, a shaft journalled in said supporting member and extending through said pivot portion coaxially therewith, a pulley carried on said shaft to support an abrasive belt thereon, a frame pivotally mounted on said pivot portion to swing about the axis of said shaft, a pulley carried by said frame at a distance from said first-named pulley to support another portion of said belt, and means for securing said frame to said supporting member in angularly adjusted position.

8. In an abrading machine, the combination of a supporting member having a pivot portion, a shaft journalled in said supporting member and extending through said pivot portion coaxially therewith, a pulley carried by said shaft to support an abrasive belt thereon, a frame pivotally mounted on said pivot portion to swing about the axis of said shaft, a pulley carried by said frame at a distance from said first-named pulley to support another portion of said belt, a clamping ring surrounding said shaft and engageable with said frame, and means for applying axial pressure to said ring to clamp said frame in angularly adjusted position.

9. In an abrading machine, the combination of spaced pulleys for supporting an abrasive belt

which presents a work-abrading flight, the axes of said pulleys being substantially parallel, a bracket on which one of said pulleys is rotatably carried, a support on which said bracket is movably mounted to tension the belt, a shaft journalled in said support, a longitudinally movable tubular member slidably and non-rotatably surrounding said shaft and having a spring seat, said tubular member having a displacing connection with said bracket, a nut threaded on said shaft and fitting non-rotatably in said tubular member, and a coiled spring within said tubular member surrounding said shaft between said nut and said seat to transmit axial movement of said nut to said tubular member.

10. In an abrading machine, the combination of spaced pulleys for supporting an abrasive belt which presents a work-abrading flight, the axes of said pulleys being substantially parallel, a bracket on which one of said pulleys is rotatably carried, a support on which said bracket is movably mounted to tension the belt, a shaft journalled in said support, a longitudinally movable tubular member slidably and non-rotatably surrounding said shaft and having a spring seat, said tubular member having a displacing connection with said bracket, a nut threaded on said shaft and fitting non-rotatably in said tubular member, a coiled spring within said tubular member surrounding said shaft between said nut and said seat to transmit axial movement of said nut to said tubular member, and spring means for urging said tubular member in the opposite direction when said nut is moved to release the pressure on said coiled spring.

11. In an abrading machine, the combination of means for supporting and driving an abrasive belt which presents a work-abrading flight, said means including a pulley over which the belt passes and toward which said flight travels, a dust-collecting hood for said pulley, and a dust-deflecting plate shiftably carried by said hood to project beyond the plane of said belt flight for directing dust into said hood, said deflecting plate having inturned flanges at opposite ends, and said deflector being shiftable laterally of the plane of said belt flight to avoid interference with long work.

12. A belt sander comprising a belt having a working face of abrasive material, a drive pulley within the belt at one end, an idler pulley within the belt at the other end, a casing surrounding the belt and the drive pulley, but having an open face to give access to one run of the working face of the belt, an end guard hood for said casing, surrounding the idler pulley and the superimposed portion of the belt, and means for detachably securing the guard hood to the casing.

13. A belt sander comprising a belt having a working face of abrasive material, a drive pulley within the belt at one end, an idler pulley within the belt at the other end, a casing surrounding the belt and the drive pulley, but having an open face to give access to one run of the working face of the belt, an end guard hood for said casing, surrounding the idler pulley and the superimposed portion of the belt, and means for detachably securing the guard hood to the casing, said means consisting of a single fastener, offset to one side of an end of the idler pulley.
